UNITED STATES PATENT OFFICE.

GEORGE H. FERNALD, OF NORTH EAST, PENNSYLVANIA.

REIN-HOLDER.

No. 853,544.

Specification of Letters Patent.

Patented May 14, 1907.

Application filed January 8, 1906. Serial No. 295,050.

To all whom it may concern:

Be it known that I, GEORGE H. FERNALD, a citizen of the United States, residing at North East, in the county of Erie and State of Pennsylvania, have invented new and useful Improvements in Rein-Holders, of which the following is a specification.

This invention relates to rein holders and consists of certain improvements of the construction thereof, as will be hereinafter fully described and pointed out in the claim.

The object of the invention is to provide a rein holder which can be readily attached to a dash, which will engage the dash so as to prevent side slipping thereof, and one in which the reins may be readily placed.

The invention is illustrated in the accompanying drawings as follows. Figure 1 shows a perspective view of the rein holder and reins, the dash and other parts being shown in dotted lines. Fig. 2 a perspective view of the rein holder. Fig. 3, a section on the line 3—3 in Fig. 2.

A marks reins and B the rein holder. The rein holder comprises the dash clamp B' and the rein clamp B². The rein clamp is formed by the spring loop b having the sides b' b². These sides have the concave inner surfaces b³ b⁴ which fit around the rib c of the dash C as clearly shown in Fig. 3. This shape of the dash clamp so engages the rib of the dash as to prevent side slipping on the dash and at the

same time it directly engages the rib of the dash so that the leather of the dash is not strained. Both of these features add to the desirability of the clamp in that they prevent largely the marring of the leather of the dash.

The rein clamp B² is formed by the side b⁵ preferably bent from the side b'; the spring loop b⁶; and the opposite side of the clamp b⁷. An extension b⁸ is arranged on the end of the side b⁷, and it is of sufficient length to permit of the reins being placed back of the extension so that the extension may be pulled outwardly by the engagement of the reins to open the clamp. The reins may then be slipped sidewise to bring them between the jaws of the clamp. This adds to the convenience of securing the reins.

What I claim as new is:

A rein holder, comprising a dash clamp adapted to extend over the top of the dash, one side of which is concave on its dash engaging surface to conform to an intermediate rib of a dash; and a rein clamp carried by the dash clamp.

In testimony whereof I have hereunto set my hand in the presence of two subscribing witnesses.

GEORGE H. FERNALD.
